WATCHMAKER'S TOOL

Edgar F. Wilton, Estes Park, Colo.

Application July 15, 1940, Serial No. 345,687

4 Claims. (Cl. 81—8)

This invention relates to improvements in watchmaker's tools and has reference more particularly to a tool for use in inserting the jewel in the roller table of an escapement.

5 In the manufacture and repair of watches having lever escapements, it is quite frequently necessary to replace the jewel or impulse pin in the roller table. Due to the small size of the roller table and of the jewel it is obviously very difficult to insert a new jewel as the same must be held in a predetermined position in an opening until secured thereto by means of shellac and heat.

10 It is the object of this invention to produce a tool especially designed for use in the operation of inserting and shellacking in place impulse pins or jewels on roller tables.

This invention, briefly described, comprises a tool made in the general shape of a pair of tweezers in which the two jaw members are formed from resilient material and biased to spaced relation. Means is provided for moving them towards each other and one of the jaws has a conical pin that will fit the opening in a roller table and hold the latter in a predetermined position relative to the jaw. The other jaw is then moved into clamping relation and after which a pivoted arm having threadedly attached thereto an abutment, is moved into position to serve as a stop for the jewel. After the jewel has been inserted in the opening shellac is applied and heat is transmitted to the assembly in sufficient intensity to melt the shellac.

Having thus briefly described the invention, the same will now be described in detail, and for this purpose reference will be had to the accompanying drawing in which the invention has been illustrated in its preferred form, and in which:

40 Figure 1 is a perspective view of the tool that forms the subject of this invention;

Figure 2 is a bottom plan view thereof;

Figure 3 is a side elevation looking in the direction of arrows 3—3, in Figure 1, the parts being shown to an enlarged scale;

Figure 4 is a section taken on line 4—4, Figure 1;

Figure 5 is a top plan view looking in the direction of arrows 5—5, in Figure 1;

50 Figure 6 is a perspective view of a roller table showing the impulse pin or jewel in position; and

Figure 7 is a section similar to that shown in Figure 4, but to a somewhat larger scale.

55 The tool which forms the subject of this in-

vention comprises two jaw members 10 and 11 which are preferably made from steel, but which may be made from any other suitable material. These jaw members have been shown as secured to a shank 12 by means of screws or bolts 13. 5 The jaws may be spotwelded or brazed to the shank 12, if desired. The shank 12 serves as a spacer and the jaw members are made of resilient material and biased to spaced relation. A screw 14 extends through an opening in jaw 10 member 10 and has a threaded connection with jaw member 11 and therefore whenever this screw is turned, the jaw members can be moved towards each other or away from each other. Since the jaws are biased to spaced relation, they 15 will move apart when the screw is turned in a direction to permit this motion. Jaw member 11 is provided with an angular portion 15 to which a piece of copper 16 has been secured by means of rivets 17. The function of this extension will 20 be hereinafter explained. In the embodiment illustrated, jaw 10 projects a short distance beyond the jaw 11 and this extension has been designated by reference numeral 18. An arm 19 is pivotally connected to the outside surface of 25 jaw 10 by means of a screw 20. A curved spring plate 21 is positioned between the head of the screw and the outer surface of the jaw so as to maintain a yielding pressure against the outer surface of arm 19. Arm 19 can be turned about 30 the screw 20 and moved from the position shown in Figure 1 to that shown in Figure 2. The free end of arm 19 is provided with a lateral extension 22 that has welded thereto an elongated hub 23. This hub is provided with a threaded opening 35 for the reception of a screw 24 whose upper end is enlarged to form an abutment 25. This screw can be rotated by means of the head 26 and the abutment 25 will move up or down in accordance with the direction of rotation.

Referring now more particularly to Figure 7, it will be seen that jaw 10 is provided on its upper surface with a conical projection 27 that serves as a positioning means for a roller table 28 which has been shown in section in Figure 7 and in 45 perspective in Figure 6. The roller table shown in Figure 6 is greatly enlarged and comprises a central cylindrical portion 29 having a circular flange 30 at its upper end and a smaller circular flange 31 at its lower end. A central opening 32 50 extends entirely through the roller table. The flange 31 has a notch 33 and directly above this an opening 34 is provided in the flange 30. Opening 34 is substantially semicircular and receives the impulse pin or jewel 35 which is held in 55

place by means of shellac that is applied thereto and heated until it melts and flows into the space between the pin and the side of the opening. The edge of jaw 11 has a notch 36 positioned 5 directly above the conical projection 27 which provides an enlarged space about the opening 34 so as to facilitate the insertion of the impulse pin.

Let us now assume that it is desired to insert 10 a jewel or impulse pin 35 in the hole 34 of a roller table. The watchmaker will first open the jaws of the tool sufficiently to permit the roller table to be inserted between them and positioned with its opening 32 over the conical positioning pin 27. The table is adjusted to bring 15 the opening 34 towards the outside as shown in Figures 4, 5 and 7. Screw 14 is now rotated to bring the jaws together, whereupon the roller table is securely clamped in position. The screw 20 24 is now turned so as to bring the abutment 25 into position beneath the opening 34 and to a height which determines the position of the lower end of the impulse pin. The jewel is now inserted 25 into the opening and allowed to rest on the abutment 25, after which a small piece of shellac is put into position on the upper surface of the roller table and when this is done, the projection 16 is moved into the flame of a gas or alcohol burner, whereupon heat will be transferred by 30 conduction to the roller table. The tool is held in operative relation to the flame until the shellac has melted, whereupon it is removed and the parts permitted to cool.

An inspection of Figure 7 will show that by 35 means of this tool, impulse pins can be readily inserted and attached to roller tables because the roller table is securely held in place and the abutment 25 prevents the impulse pin from falling through the opening.

One of the reasons it has always been very 40 difficult to insert a new impulse pin in a roller table is that the jewel or impulse pin must be held against sliding movement during the time the roller table is heated and watchmakers have 45 found that it required a great amount of experience and dexterity to hold the pin from moving during the heating operation.

In the above embodiment, a screw 14 has been 50 shown as the means for moving the jaws 10 and 11 towards each other, but this is merely illustrative of means for this purpose and can be replaced by any other equivalent means, such as a cam. A tool is provided with a handle 31 of suitable material which should preferably be a 55 poor heat conductor.

In the above description and on the drawing, a 60 specific embodiment has been described and illustrated, but it is evident that minor changes may be resorted to without departing from the invention and applicant therefore reserves the right to make such changes as fall within the scope of the appending claims.

Having described the invention, what is claimed as new is:

1. A watchmaker's tool comprising two jaws of resilient material attached to each other at one end and biased to spaced relation, means for moving the jaws towards each other to clamp between them a roller table having a flange provided with an opening for the reception of a jewel, one of the jaws having a threaded opening, a threaded jewel abutment in the opening, said abutment being adjustable by a rotary motion, and means for positioning the roller table in a predetermined relation to the abutment. 5

2. A watchmaker's tool for use in positioning a jewel in a roller table of an escapement mechanism, comprising in combination, two jaws of resilient material attached to each other at one end and biased to spaced relation, means for moving the jaws towards each other to clamp between them a roller table having a flange provided with an opening for the reception of a jewel, one of the jaws having means for positioning the roller table in a predetermined position relative thereto, an arm pivotally attached to the jaw member having the positioning means, said arm having a threaded opening, and a screw in the opening, the end of the screw forming an abutment for a jewel, the abutment surface being adjustable by a rotary movement of the screw. 10

3. A watchmaker's tool for use in positioning a jewel in a roller table of an escapement mechanism, comprising in combination, two jaws of resilient material attached to each other at one end and biased to spaced relation, means for moving the jaws towards each other to clamp between them a roller table having a flange provided with an opening for the reception of a jewel, one of the jaws having means for positioning the table in a predetermined position relative thereto, the last named jaw having a lateral 20 extension provided with a threaded opening, a screw positioned in the opening and operatively associated with the threads, the end of the screw serving as an abutment for a jewel to hold the same while it is secured in position by shellac. 25

4. A watchmaker's tool for use in positioning a jewel impulse pin in a roller table of an escapement mechanism, comprising in combination, a pair of resilient jaws secured to each other at one end and biased to spaced relation, means for moving the jaws towards each other to clamp between them a roller table, means on one jaw for positioning a roller table in a predetermined position thereon, an arm pivoted to the last mentioned jaw, means for urging the arm towards the jaw comprising a screw and a spring, the movable end of the jaw having a threaded opening, and a threaded jewel abutment member operatively positioned in the opening. 50
